UNITED STATES PATENT OFFICE.

FREDERIC BARR, OF WOODHAVEN, NEW YORK.

PULL-SWITCH.

1,158,428.

Specification of Letters Patent.

Patented Nov. 2, 1915.

Application filed April 14, 1915. Serial No. 21,409.

To all whom it may concern:

Be it known that I, FREDERIC BARR, citizen of the United States, and resident of Woodhaven, in the county of Queens and 5 State of New York, have invented certain new and useful Improvements in Pull-Switches, of which the following is a specification.

The invention claimed herein resides principally in the form of the movable switch contact, and the method of disengaging of the pawl and ratchet connection between the spring tensioning lever and the switch lever by a spring finger, and a spindle held 15 loosely by the lower porcelain base.

In the accompanying drawing I have illustrated in concrete form, several practical embodiments of the invention, wherein these objects are attained by attaching the 20 ratchet plate to the movable switch member, and insulating it from the movable switch member by insulating disks and insulating washers, and by a spring metal finger attached to the base.

Figure 1 is a cross sectional view of a pull socket switch embodying the invention. Fig. 2 is a side elevation of the same with the screw shell removed and showing the switch parts as they appear when just operated, and before the metal finger separates the spring tensioning lever from the switch lever. Fig. 3 is a cross sectional view through the center of a pull wall switch made to fit within the box or casing, of the 35 type disclosed in my Patent #1,097,207. Fig. 4 is a drop perspective view of the parts which go to make up this form of the switch. Fig. 5 is an enlarged perspective view of the movable switch member with 40 parts assembled. Fig. 6 is a view similar to Fig. 5 but showing the opposite side of the movable switch member. Fig. 7 is a cross sectional view of the movable switch member taken on line 7-7 in Fig. 5. Fig. 8 is 45 a diagrammatic view of the spring tensioning lever, and the switch lever showing them about to engage with the spring finger. Fig. 9 is a view similar to Fig. 8 but showing the spring tensioning lever and the switch lever 50 in engagement with the spring finger. Fig. 10 shows a modification in the construction of the ratchet plate in which separate rivets are used to hold the different parts of the movable switch member together.

55 Referring to the drawings more in detail,

11 designates the switch base constructed of porcelain or like insulating material provided with a pair of upwardly inclined stationary switch contacts 12 and 13 held in position by the terminals 14 and 15. Co-operating with the relatively stationary contacts is the movable switch member which is of a new and novel construction as shown in Fig. 5 and Fig. 6, being made up of a contact plate 20, which is provided with oppositely disposed downwardly inclined spring contact arms 23, in the plate portion 20 are three openings 21 and 22, into which are placed the insulating washers 24 and 25, on the lower side of the contact plate 20 is 60 placed the insulating disk 19 having three openings 21 and 22 to correspond with the three openings 21 and 22 in the contact plate 20. On the upper side of the contact plate 20 is another insulating disk 26 having three openings 21 and 22 to correspond with those in the contact plate 20. The ratchet plate 39 with two lugs 18 bent at right angles to the plate is placed on top of the insulating disk 26, the lugs passing 65 through the openings 21 in the insulating disk 26, through the insulating washer 24, and through the openings 21 in insulating washer 24, and through the openings 21 in the lower insulating disks 19, and clenched 70 as shown in Fig. 5 and Fig. 7. The tubular metal bushing 17 is then placed in the center opening 22 passing up through the lower insulating disk 19, through the insulating washer 25 in the center of the contact plate 75 20, and through the center opening 22 in the upper insulating disk 26, and through the center opening 22 in the ratchet plate and then riveted fast forming a bearing for the constructed movable switch member as 80 shown in Fig. 6 which is journaled on the central upstanding spindle 16 whose downwardly inclined spring contact arms 23 ride on the stationary contacts and insulating 85 ratchet teeth of the base. 90

The spindle 16 on which the movable parts of the switch are mounted is carried loosely by the lower porcelain base 11 as shown in Fig. 1 and Fig. 3 the square head of the spindle 16 is seated in a square recess in the porcelain base 11 which keeps the spindle from turning; the spindle 16 is held in place by the movable parts of the switch; the spring contacts the throwing spring and the nut on the upper end of the spindle. 100 105 110

The power for throwing the switch is provided by a quick-acting spring 27. This spring is possessed of considerable force and is usually closely coiled. The spring is engaged over the spindle and is anchored thereto at its upper end, as by being hooked as shown at 28 to interlock with an outstanding lug 29 on the spindle. This anchorage lug may be carried by a nut 30 screwed onto the upper end of the spindle. At its lower or free end the switch-throwing spring has a one-way driving connection with the movable switch member in the direction of rotation of said switch member. This one-way driving connection is provided in the present instance by interposing a switch lever 32 between the throwing spring and the movable switch lever, and providing this switch lever with pawls or teeth 33, engaging with shoulders provided by corresponding ratchet teeth 34, in the ratchet plate 39, on top of the movable switch member. The switch lever is pivotally engaged on the spindle, being for that purpose usually provided with a central sleeve portion 35 loosely fitting the spindle, and its ratchet teeth face forwardly so as to have driving engagement with the movable switch member in the direction of its rotation. The throwing spring is shown connected with this ratchet lever by hooking its lower end as at 37 to engage a lug 38 struck up from the lever. The spring thus has a bearing against the switch lever to rotate it and the movable switch member which it drives in the forward or circuit-changing direction.

From the foregoing it will be evident that upon a retractive or backward movement of the switch lever, the switch-throwing spring will be tensioned but no movement will be imparted to the movable switch member. When in this tensioning movement, the switch lever moves back a distance equal to one ratchet tooth, the lever drops down into engagement with a fresh ratchet tooth on the switch member and the then-tensioned spring is thus coupled in switch-throwing engagement with the movable switch member. Upon release of the switch lever the spring will then act to throw the switch member with a quick snap action. The forward throw of the switch lever is limited by a stop 10, carried by the base.

To prevent delaying or retarding of the action of the switch-throwing spring, I have provided means for automatically taking the control out of the hands of the operator once the throwing spring has been properly tensioned. Such means here takes the form of a lever 43 pivoted on the spindle above the switch lever and having a one-way connection with the switch lever for imparting a spring-tensioning movement thereto. This connection may be in the form of one or a number of downwardly struck pawls 44 on

the tensioning lever facing in a direction opposite that of the switch movement and arranged to engage shoulders provided by a corresponding number of seats 45 in the switch lever. Disengagement of this pawl and ratchet connection between the spring-tensioning lever and switch lever is automatically effected when the spring is tensioned by supporting the tensioning lever so that it cannot follow the switch lever when that lever drops down at the time of its engagement with a fresh ratchet tooth on the switch member, by a spring finger 32 attached to the base that separates the spring tensioning lever from the switch lever substantially at the instant of the engagement of the switch lever with the new ratchet tooth on the movable switch member. The side edge of the spring tensioning lever 49 is turned or bent up slightly at 49^a and the side edge of switch lever 32^a is turned or bent down slightly at 32^b as shown in Figs. 8 and 9 and Fig. 4 so as to form a guide for the spring finger.

The spring finger is so adjusted that when the tensioning lever carries the switch lever forward to the instant of its engagement with the ratchet tooth on the movable switch member, the spring finger forces the tensioning lever up and the switch lever down, the spring finger is made of spring metal and is secured to the porcelain base by a screw.

The spring-tensioning lever is preferably made with a hub portion 48 pivotally engaging over the switch-throwing spring and the central body portion of the lever is usually "domed" or bossed up, as indicated at 49 to accommodate and cover the connection between the throwing spring and the switch lever (Fig. 1). To permit the placing of the tensioning lever on the spindle without removing the outstanding anchorage lug, the lever is usually formed with a radial slot 50 large enough to pass over the lug. The tensioning lever is returned back into driving engagement with the switch lever by a spring 52 having its lower end hooked into the radial slot 50 in the tensioning lever and its upper end anchored to the spindle. This spring can be relatively light since the purpose is merely to swing the tensioning lever back into holding engagement with the switch lever.

The anchorage for the returning spring 52 in the first form of the invention is of novel construction in that it comprises a flanged bushing 53 fitting within the upper end of the spring so as to form a bearing therefor and slotted in one side at 54 so as to slip down over the anchorage lug 29. This bushing is usually placed on the spindle, over the nut 30, which may be round to fit within the bushing and it may be held in place by a nut 55 applied to the end of the spindle. The flange 58 of the bushing is

provided with a notch or notches 56 to take the upper end of the returning spring. The anchorage lug 29 when engaged in the slot 54 will hold the bushing against turning when the spring is thus engaged therewith.

In operating, a pull on the chain draws over the spring-tensioning lever and this lever being during such movement positively connected with the switch lever, the switch lever also is moved and the switch throwing spring which is connected with it is thereby placed under tension. The movable switch member remains stationary during this movement, the teeth of the switch lever sliding back idly over the teeth on the switch member. At the end of a movement sufficient to place the throwing spring under proper switch-throwing tension the switch lever has traveled far enough back for its teeth to drop down into engagement with a new set of teeth on the switch member. At the time the switch lever, and hence the tensioned spring, is thus automatically coupled in fresh engagement with the switch member, the tensioning lever is supported by the spring finger and so cannot follow the switch lever as that lever drops to engage the new ratchet teeth. The switch lever in coupling itself to the movable switch member, thus in effect drops from beneath the tensioning lever and this drop is sufficient to uncouple the connection between the tensioning lever and switch lever. The switch lever being now freed from the tensioning lever and coupled to the movable switch member, is thrown suddenly by the throwing spring, thereby making or breaking the circuit as the case may be, with a quick snap action. The closely coiled throwing spring forces the movable switch member down firmly into engagement with its relatively stationary contacts thereby insuring always a good contact. As the pull on the chain is released the returning spring 52 returns the tensioning lever back into holding engagement with the switch lever. The stop 10 for the switch lever may be utilized here also to limit the return movement of the spring-tensioning lever.

My invention provides a switch of but few and simple parts, having a quick-make and quick-break action, and therefore capable of carrying a considerable current load. The arc-interrupting construction at the switch contacts in addition to preventing the formation of arcs, prevents heating and burning of the contact parts. The control may be had by means of a pull chain, a lever, or other form of handle as will be apparent to those skilled in the art and it will be understood that other modifications such as come within the scope of the invention may be resorted to. It will be further understood that the terms employed herein are terms of description rather than of limita-

tion, except so far as may be required by the prior art.

What I claim is:—

1. In an electric switch, a movable switch member, a movable switch lever having its side edge turned down, a spring tensioning lever having its side edge turned up and a spring finger engaging the movable switch lever and the spring tensioning lever and separating them at the moment the switch lever drops into connection with switch member.

2. In an electric switch, a movable switch member, a movable switch lever having a driving connection with the movable switch member and having its side edge bent down, a throwing spring, one end attached to said switch lever, the other end to an anchor lug on end of the spindle, a movable spring tensioning lever having a driving connection with the switch lever and having its side edge bent up, a throwing spring attached to said tensioning lever to return it to its first position, and a spring finger for disengaging the driving connection between spring opening tensioning lever and the switch lever.

3. In an electric switch, a movable switch member, a movable switch lever having a driving connection with the movable switch member and having its side edge bent down, a throwing spring, one end attached to the switch lever, the other end to an anchor lug on end of the spindle, a movable spring tensioning lever having a driving connection with the switch lever and having its side edge bent up, a throwing spring attached to the tensioning lever to return it to its first position and means for disengaging the driving connection between spring tensioning lever and the switch lever.

4. In an electric switch, a movable switch member having openings in the flat portion, insulating washers to fit in said openings, insulating disks on the upper and lower sides of said switch member with openings to correspond with those in the insulating washers in the switch member, a ratchet plate with two lugs to pass through the openings in said insulating disks and insulating washers in the switch member and clenched fast on the lower side of the lower insulating disk, a tubular metal bushing fitted into the center opening and fastened there to form a bearing.

5. In an electric switch, a movable switch member having openings in flat or plate portion, insulating washers to fit in said openings, insulating disks on upper and lower side of switch member, a ratchet plate on top of upper insulating disk, a tubular metal bushing in the center opening, and means for fastening them all together.

6. In an electric switch, the combination of a movable switch member, a ratchet plate

- having two lugs by which it can be attached to, and insulated from the movable switch member by insulating washers and insulating disks and a metal bushing fastened into center opening to form a bearing.
7. In an electric switch, a movable switch member having openings in the flat or plate portion, insulating washers in the said openings, an insulating disk on the upper side of switch member, with openings to correspond with those in the insulating washers in the switch member, an insulating disk on the lower side of the switch member with openings to correspond with those in the insulating washers in the switch member, a ratchet plate on the top side of the upper insulating disk, a tubular metal bushing in the center opening forming a bearing and means for fastening them all together.
8. In an electric switch, a movable switch member having insulating washers in plate portion, a ratchet plate, insulating disks on upper and lower sides of switch member and all held together by two rivets and the tubular metal bushing in the center.
9. In an electric switch, a switch base having a square recess, a spindle having a square head, seated in the square recess, a movable switch member journaled on said spindle, a switch lever pivoted on the spindle and having a one way driving connection with the movable switch member in the direction of its rotation, a switch throwing spring engaging said switch lever, a spring tensioning lever having a one way driving connection with the switch lever in a direction opposite

to that of the switch movement and a spring finger engaging the switch lever and the spring tensioning lever in the spring tensioning movement thereof to assist in separating the connection between the spring tensioning lever and the switch lever.

10. In an electric switch, a switch base having a square recess in its lower portion, a spindle having a square head seated in the recess and loosely held by the base, a switch member pivoted on the spindle, a switch lever pivoted on the spindle above said switch member, a switch throwing spring encircling the spindle above said lever anchored to the spindle at its upper end and connected into the switch lever at its lower end, holding the spindle in position.

11. In an electric switch, a movable switch member, a movable switch lever engaging said switch member, a spring tensioning lever, means connecting said switch lever and spring tensioning lever in the spring tensioning movement of said tensioning lever and a separating finger engaging between the tensioning lever and switch lever in the spring tensioning movement of said lever to thereby disconnect the spring tensioning lever from the switch lever.

Signed at borough of Manhattan, New York city, in the county of New York and State of New York this 9th day of April, A. D. 1915.
